UNITED STATES PATENT OFFICE.

WALTER PRESTON HENDON, OF DALLAS, TEXAS.

DESIGN FOR A PLOW-BEAM FOR TRIPLE-DISK PLOWS.

SPECIFICATION forming part of Design No. 33,112, dated August 21, 1900.

Application filed May 17, 1900. Serial No. 17,070. Term of patent 14 years.

To all whom it may concern:

Be it known that I, WALTER PRESTON HENDON, a citizen of the United States, and a resident of the city of Dallas, county of Dallas, 5 and State of Texas, have invented and produced a new and original Design for Plow-Beams for Triple-Disk Plows, of which the following is a specification, reference being had to the accompanying drawings, forming 10 part thereof.

Figure 1 is a plan view of a plow-beam embodying my design. Fig. 2 is a side elevation of the beam shown in Fig. 1.

As shown in the drawings, the beam is in 15 the form of an open frame having two long substantially-parallel frame members A, B, and a third member C, substantially parallel with the members A and B for a part of its length and bent at the forward part at an incline, as shown at c, to join the member B. 20 At the forward end the members A and B have between them a spacing-block D. The

rear ends of the members A, B, and C extend substantially parallel with each other and at an angle to the main portions of the members. These angular ends are indicated, respectively, at A' B' C'. At the rear end of the part C' is a bracket E, the configuration of which is shown in the drawings. Between the ends A', B', and C' are spacing-pieces, 25 indicated, respectively, at F and G.

The essential feature of the design is the open frame having the parallel members A, B, and C terminating in angular ends A' B' C'.

Having described my invention, what I 35 claim as new, and desire to secure by Letters Patent, is—

The design for a plow-beam for triple-disk plows as herein shown and described.

WALTER PRESTON HENDON.
